METHOD OF FORMING PLATE GANGS FOR
MULTICOLOR PRINTING

Bernard F. Heck, St. Paul, Minn.

Original application June 27, 1932, Serial No. 619,367. Divided and this application September 23, 1933, Serial No. 690,687

6 Claims. (Cl. 101—401.2)

My invention relates to the forming of plate gangs for multi-color printing and has for an object thereof to provide a novel and effective method by which accurate register may be had

5 in multi-color printing from gangs of plates, an additional object of the invention being to provide a method of the instant character capable of practical application in connection with a simple device of the nature disclosed in my co-pending application for patent, Ser. No. 619,367, from which this application is divided.

Another object of the invention resides in providing a method in which the several plates of the various gangs are similarly formed with 15 gauge holes or otherwise machined for gauging contact with cooperating gauging elements and in which the ultimate relation of each plate with respect to the companion plates of its respective gang is precisely determined individually and in 20 the same manner as each corresponding plate of each of the other gangs.

A further object of the invention resides in providing a method, as above, in which the plates of each gang, relatively disposed in their 25 ultimately defined relation, are permanently secured in such relation to a suitable backing.

More specifically, the invention resides in a method of forming a set of composite electro-type gangs in which method the several plates 30 of the different gangs for different colors are successively grouped upon a device having individual gauge members for the individual plates of a gang, said method involving the attachment of the plates of each gang in their gauged relation to a suitable backing while disposed upon 35 said device so that the corresponding plates in the several gangs of the set have identically the same relation with respect to their companion plates in their respective gangs.

40 These and other objects of the invention will more fully appear in the following description.

In the accompanying drawings, which, among other things, illustrate a device by means whereof my improved method may be carried out, 45 Figs. 1, 2, 3, and 4 are perspective views of ordinary engraved plates from which electro-type plates used in color printing are made, one of such plates being employed for each of the different colors used; Fig. 5 is a view of the ultimate print; Fig. 6 is a perspective view of an electro-type plate made from an engraved plate, as shown in Fig. 1, and having gauge holes drilled therein; Fig. 7 is a perspective view of a mounted gang, the several electro-type plates 50 comprising said gang being like that shown in Fig. 6; Fig. 8 is a sectional view taken on line 8—8 of Fig. 7; Fig. 9 is a perspective view of an assembling device capable of use for carrying out my improved method; Fig. 10 is a fragmentary 55 sectional view taken as on line 10—10 of Fig. 11 and drawn to a larger scale; Fig. 11 is an elevational sectional view taken as on line 11—11 of Fig. 9 and drawn to a larger scale; and Fig. 12 is a perspective view of one of the gauge blocks employed.

5 In making engravings to be used in forming electro-type color plates, the engraver customarily cuts gauge marks at top and bottom of the engravings which marks show on the electro-type plates and are used in stationing the different 10 color plates in a proof press to register the different prints taken therefrom.

Upon being satisfied with the showing made by the electro-type plates in the color proof press, the electrotypewriter has then to mount like plates 15 in gangs, it being his desire, of course, that the corresponding plates of the several gangs occupy corresponding relations with respect to the companion plates in their respective gangs. Ordinarily, the different electro-type plates of the several gangs are as accurately as possible similarly trimmed with respect to the gauge marks thereon with the view of assembling the plates of each gang in abutting relation on a mounting block. In following this practice, errors of more 20 or less magnitude occur and are sometimes greatly multiplied before the individual plates of a gang are ultimately secured to their respective mounting blocks. Due to such errors it is 25 impossible invariably to secure perfect register 30 of prints from all of the corresponding plates of the different gangs employed in a multi-color job. The employment of my invention in forming sets of color gangs practically eliminates all 35 chance of error and results in substantially accurate register, regardless of the number of plates incorporated in each gang.

In carrying out my improved method, an assembling device is employed, one form of such device being shown in Figs. 9, 10 and 11. This 40 device includes a bed 10 supported on legs 12, the bed 10 being of any suitable length. Upon said bed 10 and at the forward edge thereof is mounted a front guide 13 consisting of a bar of metal formed from end to end thereof with a 45 dovetailed groove 14 opening at the top of the bar.

Formed in the bed 10 at right angles to the guide 13 are parallel slots 15. A way 18 slidably disposed upon the bed 10 overlies the slots 50 15, said way being substantially the same length as the guide 13. This way 18 is formed with threaded bores 19 (Figs. 10 and 11) to receive clamping bolts 20 which extend through the slots 15 and hold said way in various adjusted 55 positions with respect to the guide 13.

The way 18 is constructed with a dovetailed tongue 22 extending along the upper side thereof, said tongue being adapted to be received in a dovetailed slot 23 formed in the underside 60

of a guide 24 similar in form to the guide 13. The guide 24 is also provided with a dovetailed slot 25 corresponding with the dovetailed slot 14 of guide 13. The guide 24 may be locked 5 against movement with respect to the way 18 by a number of thumb screws 34 threaded into said guide from the back thereof. These thumb screws 34 engage a gib 35 disposed within the slot 23 and extending along one edge of the 10 tongue 22. As said screws 34 are tightened the gib 35 is forced against the tongue 22 which holds the guide 24 from movement on the way 18.

In conjunction with the two guides 24 and 13 15 a number of supports 26 are employed which are constructed from blocks of metal beveled along the surfaces 57 and 58 thereof to snugly fit within the two grooves 14 and 25 of the guides 13 and 24. These blocks are inserted 20 endwise into said grooves and may be slid therealong to occupy any desired adjusted position therein. Each of the blocks 26 is provided at the top thereof with a gauge pin 27 and is formed with a threaded bore as at 29 to receive 25 a set screw 30. The lower end of this bore is reduced in diameter, as shown, providing an internal shoulder 60. A seating element 32, disposed in the reduced portion of the bore 29, has a head 61 contained within the bore proper 30 which cooperates with the shoulder 60 and keeps the seating element 32 from becoming displaced from the block 26 at such time as said block may be removed from its guide. The set screw 35 is formed with a square hole 31 in its upper end by means of which a suitable wrench may be applied thereto. When one of the gauge blocks 26 is mounted in either of the grooves 14 or 25, said block may be firmly locked in position by turning the screw 30 down against 40 the lower wall 33 of the guide. This urges the beveled walls 57 and 58 of the block into engagement with the adjacent walls of the slots 14 or 25 and holds the block locked against movement.

45 I have shown in Fig. 5 an ultimate print to be printed and in Figs. 1 to 4 inclusive, the various engraved plates from which electrotypes used in printing this figure would be made. The print illustrated is printed in four colors, blue, red, gold and black and the engraved plates for these colors are designated by the reference characters 36, 37, 38 and 39 in Figs. 1 to 4 respectively. A number of the electrotypes made from plate 36 are indicated at 36a, 36b 50 and 36c in Fig. 7, a similar electrotype being indicated at 36a in Fig. 6. Corresponding electrotype plates made from the engraved plates 37, 38 and 39 would be required, of course, to complete the set. On the body 41 of each of 55 the various electrotypes is a raised portion 40 corresponding with the raised portion 40a of the engraved plate 36. The metal of the body 41, except at the raised portion thereof is "dead metal", its primary purpose being to provide 60 means for attaching the plate proper to the mounting therefor. In this "dead metal", the gauge marks 42 and 43 (Fig. 6) appear in simulation of the corresponding gauge marks 42a and 43a (Fig. 1) formed in the original engraving.

70 In multi-color proof printing, it has been the practice to some extent to drill gauge holes in the electrotype plates, such holes having a definite relation with respect to the gauge marks

thereof and to successively mount such plates on guide pins in the bed of a proof press whereby registered printing of the various plates could be accurately carried out to form the proof print. In carrying out my present method, such gauge holes may be utilized. In Fig. 6, I have shown a plate 36a in which has been drilled two gauge holes 44 and 45. In thus drilling a plate in the type of machine available for the purpose, the plate is mounted upon a support and adjusted under a locating glass until one or the other of the gauge marks 42 or 43, as the case may be, registers with a cross hair associated with said glass. When the plate is properly located, a drill is brought into action, said drill being so mounted and operated as to drill the holes at predetermined locations with respect to the gauge mark of the plate upon which sight is taken. All the electrotype plates taken from the engravings 36, 37, 38 20 and 39 are drilled in the same manner with respect to each gauge mark, each plate then having gauge holes 44 and 45, the holes in each plate being located in identically the same relation with respect to their gauge marks 42 and 25 43. In addition to the gauge holes two holes 50 are drilled in the "dead metal" of the plates for a purpose soon to be explained.

55 In the mounting of the plates upon the assembling device the following procedure is employed: The thumb screws 34 and the bolts 20 are first loosened so that the guide 24 may be moved in two directions upon the bed 10. A block 26 is next inserted in the slot 14 of guide 13 at approximately the desired locality. This block is then locked in place through its set screw 30. In a similar manner another block is mounted in approximately the proper location in the guide 24 and locked in place. One of the plates for example 36a, is then placed 40 upon the assembling device and the register holes 44 and 45 thereof caused to receive the gauge pins of the two blocks mounted in the guides 13 and 24. The plate 36a is then squared up with respect to the guide 13, the guide 24 45 being moved lengthwise on the way 18 and said way being moved transversely on the bed 10 as may be required in accomplishing the purpose. When the guide 24 is properly located all of the screws 34 and the bolts 20 are tightened to 50 hold the parts 24 and 18 rigidly in position. If desired, a second plate may be temporarily used to procure parallelism between the two guides. In such case, this plate would be mounted upon two gauge pins situated at the far ends of the 55 guides 24 and 13, whereby parallel spacing of the guides could be readily procured. With the guide 24 properly positioned and clamped, additional gauge blocks are applied and secured to the guides 13 and 14, the distances between 60 gauge pins 27 in the blocks 26 in each guide being made sufficient to accommodate the width of the plates and being caliperized for accuracy. Thus, all of the blocks 26 for all of the electrotypes to be incorporated in a gang are assembled 65 and held in selected relation with respect to each other.

70 With the blocks 26 in place in the guides 13 and 24, the remaining plates going to make up the gang are applied, one to each pair of gauge pins, and pressed down to rest upon the upper edges of said guides 13 and 24. In Fig. 9 the plates 36a, 36b and 36c, made as from the engraving 36, have been illustrated as mounted upon the device. A filler block 48 of wood is 75

then inserted between the two guides 13 and 24 and beneath the various plates 36a, 36b and 36c. Upon this block is placed a metal backing 49 which snugly underlies said plates. Solder is then flowed into the holes 50 forming solder keys 51 securing the plates to the backing 49. The structure thus formed is removed en bloc from the gauge pins 27 without disturbing the position of the blocks 26, the 10 plates and backing being then trimmed down to the proper dimensions, the end portions of said plates containing the gauge marks and gauge holes being cut away to complete the construction of the gang.

15 The several plates for another color gang are placed upon the assembling device, the same being readily applied to the gauge pins 27 without disturbing the position of the blocks 26. These plates are then secured to a backing 20 therefor and then removed from the assembling device and trimmed as in the case of the gang first described. The same operation is repeated for the several plates of each of the remaining color gangs, each gang being built up without 25 changing the position of the pins 27. After all of the gangs have been completed it will be found that each plate of each gang will accurately register with the corresponding plate of each of the other gangs so that impressions 30 may be taken from all of the plates and brought into absolute register.

A set of color gangs, as formed by the method hereinabove described, would be used preferably as master plates for making other electrotypes. 35 If desired, however, the different gangs of a set, as I construct them, may themselves be used for printing, in which case they would be attached to a suitable wood block. And, too, original hand engraved plates, zinc etchings, copper 40 etchings, photoengravings and stereotypes may be assembled in gangs in accordance with the present invention to be used for printing or duplicating.

Through my improved method, the various 45 electrotypes of a gang may be mounted accurately in predetermined relation with respect to one another. The corresponding plates of the different gangs have exactly the same relation with respect to the other plates of their respective gangs so that absolute register is procured. Even though an irregularity occurs, for example, 50 as in the clamping of the blocks 26 in the guides 13, 24, the same irregularity occurring in each gang will not affect register in printing. As 55 many plates as desired can be associated in a single gang without accumulative error and the relation between plates of each gang of a set will be identical in each instance.

Having described my invention, what I claim 60 as new and desire to protect by Letters Patent is:

1. The method of forming plate gangs for multi-color printing which consists in drilling gauge holes in the several plates of a gang in identical positions relative to the register marks thereon, in mounting the plates upon a support having gauge pins arranged to enter the gauge holes in the plates and establish a definite relationship between such plates, in attaching a 65 backing to the plates while mounted on said support and disposed in said definite relationship by said pins, and in thereafter removing the formed plate gang from said support and gauge pins.

2. The method of forming plate gangs for multi-color printing which consists in drilling gauge holes through the end portions of the several plates of a gang in identical positions relative to the register marks thereon, in mounting the plates upon spaced supports having gauge pins arranged to enter the gauge holes in the plates and establish a definite relationship between such plates, in attaching a backing, 10 disposed between the supports, to the intermediate portions of the plates while mounted on said supports and held in said definite relationship thereon by said pins, in removing the formed gang from said supports and gauge pins, and in trimming off said end portions of said 15 plates in conformity with said backing.

3. The method of forming plate gangs for multi-color printing which consists in drilling gauge holes in the plates of a gang in identical positions relative to the register marks thereon, then applying the plates to gauge pins fixed and arranged to enter the gauge holes in the plates for establishing a definite relationship therebetween, then attaching a backing to the plates 20 while disposed in said definite relationship by 25 said pins, and then removing the formed gang from said pins.

4. The method of forming plate gangs for multi-color printing which consists in drilling gauge holes in the several plates of a gang in identical positions relative to the register marks thereon, in mounting the plates upon a support having gauge pins thereon arranged to enter the gauge holes in the plates with portions of the plates superimposing a backing, in drilling holes 30 through the dead metal of said plates, in casting 35 keys into said holes and to said backing to hold the plates attached to the backing, and in removing the formed gang en bloc from said support and gauge pins.

5. The method of forming plate gangs for multi-color printing which consists in arranging a plurality of gauge members, two for each plate of a gang, to correspond with a predetermined arrangement of the plates in the gang to 45 be provided, in forming engaging portions in the several plates in identical positions relative to register marks thereon for cooperation with the gauge members, in applying the plates of the gang to said gauge members, in permanently attaching a backing to said plates while they are held in their predetermined relationship through the cooperation of each thereof with its respective gauge members, and in finally removing the completed gang, plates and backing en bloc, 50 from said gauge members.

6. The method of forming plate gangs for multi-color printing which consists in arranging gauge members, a plurality thereof for each plate of a gang, to correspond with a predetermined arrangement of plates in the gang to be provided, in similarly forming the several plates with engaging portions for cooperation with the gauge members, in applying the plates of the gang to said gauge members, in permanently attaching a backing to said plates while they are held in their predetermined relationship through the cooperation of each thereof with its respective gauge members, and in finally removing the completed gang, plates and backing en bloc, 65 70 from said gauge members.

BERNARD F. HECK.
